UNITED STATES PATENT OFFICE

138,024

DESIGN FOR A PENDANT OR SIMILAR ARTICLE

Lonnie Barber, Danville, Va., assignor of fifty per cent to Irene Pritchett, Danville, Va.

Application March 20, 1944, Serial No. 112,967

Term of patent 7 years

(Cl. D45—15)

To all whom it may concern:

Be it known that I, Lonnie Barber, a citizen of the United States, residing at Danville, in the county of Pittsylvania and State of Virginia, have invented a new, original, and ornamental Design for a Pendant or Similar Article, of which the following is a specification, reference being had to the accompanying drawing, forming part thereof.

Figure 1 is a front elevational view of a pendant or similar article, showing my new design, and

I claim:

The ornamental design for a pendant or similar article, as shown.

LONNIE BARBER.
